UNITED STATES PATENT OFFICE

166,518

DEEP-FAT FRYER

Arthur D. Altemiller, Afton, Mo., assignor to Hercules Steel Products Corporation, Galion, Ohio, a corporation of Delaware

Application January 4, 1952, Serial No. 17,944

Term of patent 14 years

(Cl. D81—10)

To all whom it may concern:

Be it known that I, Arthur D. Altemiller, a citizen of the United States, residing in Afton, St. Louis County, State of Missouri, have invented a new, original, and ornamental Design for a Deep-Fat Fryer, of which the following is a specification, reference being had to the accompanying drawing, forming a part thereof.

Fig. 1 is a perspective view of the front and top of a deep-fat fryer, embodying my new design; and

Fig. 2 is a side elevational view thereof.

The rear side is a plain unornamented wall.

I claim:

The ornamental design for a deep-fat fryer, substantially as shown and described.

ARTHUR D. ALTEMILLER.
